UNITED STATES PATENT OFFICE.

FREDERICK W. FREY, OF BOSTON, MASSACHUSETTS, ASSIGNOR TO THOMAS SHEPARD AND GEORGE FREY, OF BOSTON, MASSACHUSETTS.

WRENCH.

SPECIFICATION forming part of Letters Patent No. 759,260, dated May 10, 1904.

Application filed September 17, 1903. Serial No. 173,505. (No model.)

To all whom it may concern:

Be it known that I, FREDERICK W. FREY, of Boston, in the county of Suffolk and State of Massachusetts, have invented certain new and useful Improvements in Wrenches, &c., of which the following is a specification.

This invention relates chiefly to wrenches, and especially to pipe-wrenches intended to act on polished or nickeled pipe or tubing.

10 The invention may, however, be embodied in wrenches of other types, and certain features of the invention may be embodied in other mechanical devices, such as lifting-jacks, &c.

The invention has for its object, first, to 15 provide means for applying hand-power to a movable member, such as a wrench-jaw or the equivalent part of a lifting-jack in such manner as to utilize the power advantageously in operating said movable member, so that

20 when the invention is embodied in a wrench the said jaw will be caused to exert all the pressure required to prevent the two jaws from slipping on the work when turning in one direction, the jaws being caused to automatically release their hold on the work when 25 turning in the opposite direction.

The invention also has for its object to provide improved means for adjusting the jaws of a pipe or other wrench.

30 The invention consists in the improvements which I will now proceed to describe and claim.

Of the accompanying drawings, forming a part of this specification, Figure 1 represents 35 a side elevation of a pipe-wrench embodying my invention. Fig. 2 represents an edge view of the same. Fig. 3 represents a section on line 33 of Fig. 2. Figs. 4 and 5 represent modifications.

40 The same reference characters indicate the same parts in all the figures.

Referring to Figs. 1, 2, and 3, *a* represents the stock or body of a pipe-wrench, the same being provided in this embodiment of my invention with a suitable guide for a sliding shank or holder *b*, the latter being provided with an adjustable outer jaw *c*. Means are provided for adjusting the shank or holder *b*

to move the outer jaw *c* toward and from the inner jaw *d*. The jaws *c* and *d* are here shown 50 as provided with semicircular grasping-faces to conform to the periphery of a pipe; but it is obvious that the grasping-faces of the jaws may be of any other suitable or desired form. The preferred means for adjusting the shank 55 or holder *b* comprise an adjusting-slide *e*, which is movable lengthwise in a suitable guide *f*, fixed to the stock *a*, and is also adapted to swing laterally in said guide to separate a hook or engaging member *e'* at its outer 60 portion from a corresponding recess *b'*, formed for its reception in the shank or holder *b*. The inner end portion of the adjusting-slide *e* is cylindrical and provided with a screw-thread. With the screw-thread is engaged an adjusting-nut *g*, which is held yieldingly against the guide *f* by a spring *h*, interposed between the guide and a shoulder *e''* on the slide *e*. The spring *h* serves two purposes—namely, to exert endwise pressure on the adjusting-slide in the direction required to hold the nut *g* against the guide *f*; and, secondly, to restore the slide *e* to its position of engagement with the holder *b* after the slide has been tipped or swung away from said holder. It 75 will be seen that the rotation of the nut *g* will cause an endwise movement of the adjusting-slide *e* in one direction or the other, the nut being held by the spring *h* against the guide *f*. The described provision for swinging the 80 adjusting-slide quickly into and out of engagement with the shank or holder *b* enables said shank or holder to be quickly engaged with and disengaged from the adjusting-slide, the holder when disengaged from the slide 85 being adapted to be moved quickly endwise to any desired extent and removed from the stock if desired. When the holder *b* is engaged with the adjusting-slide, it partakes of the movement imparted to the slide by the rotation of the adjusting-nut *g*.

The jaw *d* is loosely connected with or mounted in the stock *a* in such manner that it is free to have a limited independent movement toward and from the jaw *c* independently of the latter and of the adjusting means,

the object of this independent movement being to cause the jaw d to exert a clamping pressure on the work when the stock is being swung in one direction and to release the work when the stock is being swung in the opposite direction. I have provided means whereby pressure exerted on the handle i when the wrench is swung in one direction causes the jaw d to exert clamping pressure on the work, 5 pressure exerted in the opposite direction on the handle causing the said pressure to be removed from the work. The handle i is pivoted at i' to the stock a and is formed as a two-armed lever, having a shorter arm i'' within the stock.

10 j represents a lever pivoted at j' to the stock and having a shorter arm j'' , formed as a cam, which bears on the under side of the loose jaw d and a longer arm j''' .

15 k represents an intermediate lever pivoted at k' between the levers i and j , the lever k having a shorter arm k'' , engaged with the longer arm j''' of the lever j , and a longer arm k''' , engaged with the shorter arm i'' of the lever i , all as shown in Figs. 1 and 3. The levers i , k , and j are therefore compounded, their arrangement being such that when pressure is exerted on the handle-lever i in the direction of the arrow in Fig. 1 the cam j'' will be 20 caused to exert a powerful outward pressure on the jaw d , causing the latter to firmly grasp a piece of tubular work inserted between the jaws, the work being grasped so firmly that it is practically impossible for the 25 jaws to slip upon it and mar its surface. When pressure is exerted in the opposite direction upon the handle i , the cam j'' releases the jaw d , and the jaws are free to slip backwardly 30 upon the work.

35 l The described provision for automatically exerting clamping pressure upon one of the jaws of the pipe-wrench enables the grasping-faces of said jaws to be provided with smoothly-polished surfaces, which cannot mar or deface polished or nickelized pipes. The jaws are 40 preferably detachably secured, so that they can be removed and other jaws of different sizes substituted for them. As here shown, the jaw c is secured by a screw c' to the holder

45 b , the jaw d being provided with a flanged projection d' , which is movable lengthwise in a corresponding groove a' , formed for its reception in the stock a , the depth of the groove a' being sufficient to permit the described movements of the jaw d toward and from the jaw c .

50 The above-described invention has been successfully applied by me to pipe-wrenches; but I do not limit myself to such appliances, it being obvious that the advantage of the loose jaw, a lever having a shorter arm engaged with said jaw, and means for moving said lever to apply a clamping pressure to the loose jaw will apply to various other kinds of wrenches. It is also

60 obvious that a system of levers compounded as above described, one of said levers constituting a handle to be operated by hand-power, 65 may be utilized in an appliance such as a lifting-jack, the inner lever having the cam being arranged to act directly upon the weight to be raised or upon a plate or member d'' in contact 70 with said weight, as shown in Fig. 5. In said figure I have shown two intermediate levers interposed between the lever j , having the cam j'' for its shorter arm and the lever i constituting the operating-handle.

75 In Fig. 4 I show a modification in which the lever i acts directly upon the lever j , there being no intermediate lever.

I claim—

1. A wrench comprising a head, grasping-jaws supported thereby, one of the jaws being loose, a lever pivoted to the head and having a shorter arm and a longer arm, the former supporting the loose jaw, and means for applying pressure to the longer arm of said lever 80 to exert a clamping pressure on the loose jaw.

2. A wrench comprising a head, grasping-jaws supported thereby, one of the jaws being loose, and a series of compounded levers pivoted to the head, one of said levers supporting 85 the loose jaw, while another is arranged to serve as the handle of the wrench.

3. A wrench comprising a head, grasping-jaws supported thereby, one of the jaws being loose, a jaw-supporting lever pivoted to the 90 head and having a cam forming the shorter arm of the lever, a handle pivoted to the head and having arms of unequal length, and an intermediate lever pivoted to the head and having a longer arm engaging the shorter arm 95 of the handle, and a shorter arm engaging the longer arm of the cam-lever.

4. A wrench comprising a head, an inner jaw, an adjustable outer jaw having a slidable shank or holder, an adjusting-slide separably 100 engaged with said holder and adapted to swing laterally to separate it from the holder, an adjusting-nut engaged with a screw-threaded portion of said slide, and a spring which normally holds the slide in engagement with the 105 jaw-holder and also holds the adjusting-nut against an abutment on the head.

5. The combination of a head or body, an adjustable member thereon, and a series of compounded levers pivoted to the head, one 110 of said levers having its shorter arm formed as a cam which engages the adjustable member, while another lever is formed as an operating-handle.

115 In testimony whereof I have affixed my signature in presence of two witnesses.

FREDERICK W. FREY.
